DISPLAY BOX

Jerome G. Hahn, Englewood, N.J., assignor to Jacoby-Bender, Inc., Woodside, N.Y., a corporation of New York

Filed Apr. 7, 1965, Ser. No. 84,657

Term of patent 7 years

(Cl. D58—12.7)

FIG. 1.

FIG. 3.

FIG. 2.

FIG. 4.

FIG. 5.

FIG. 1 is a rear elevational view of a display box showing my new design;

FIG. 2 is an end elevational view thereof;

FIG. 3 is a bottom plan view thereof;

FIG. 4 is a top plan view thereof; and

FIG. 5 is a three-quarter perspective view thereof, on a reduced scale, with the cover thereon being shown in its open position.

I claim:

The ornamental design for a display box, as shown.
